DESIGN FOR A FRAME FOR LABELING MACHINES OR SIMILAR ARTICLES

George W. von Hofe, Bound Brook, N. J., and
Bernard D. Dans, Brooklyn, N. Y., assignors to
New Jersey Machine Corporation, Hoboken,
N. J., a corporation of New Jersey

Application May 26, 1936, Serial No. 62,850

Term of patent 14 years

To all whom it may concern:

Be it known that we, George W. von Hofe, a citizen of the United States and resident of Bound Brook, in the county of Somerset and State of New Jersey, and Bernard D. Dans, a citizen of the United States and resident of the Borough of Brooklyn, in the county of Kings, city and State of New York, have invented a new, original, and ornamental Design for a Frame for Labeling Machines or Similar Articles, of which the following is a specification, reference being had to the accompanying drawing, forming part thereof.

Fig. 1 is a front elevational view in perspective of a frame for labeling machines or similar articles showing our new design; and

Fig. 2 is a rear perspective elevational view thereof.

We claim:

The ornamental design for a frame for labeling machines or similar articles as shown.

GEORGE W. von HOFE.
BERNARD D. DANS.
